WILLIAM EDWARD CHESNEY, OF HALIFAX, NOVA SCOTIA, CANADA.

RAILROAD-TIE.

1,215,112.

Specification of Letters Patent.

Patented Feb. 6, 1917.

Application filed March 18, 1916. Serial No. 85,160.

To all whom it may concern:

Be it known that I, WILLIAM E. CHESNEY, a subject of the King of Great Britain, and a resident of Halifax, in the county of Halifax, Province of Nova Scotia, Canada, have invented a new and Improved Railroad-Tie, of which the following is a full, clear, and exact description.

My invention relates to a reinforced concrete railroad tie and has for a purpose to provide a tie of the character to meet commercial requirements with respect to strength and initial cost for manufacture and installation, as well as the cost of up-keep and replacement.

The invention also has for its object to provide a tie of the class referred to so formed as to prevent the result known as a center-bound track due to the center portion 20 of the tie bearing harder on the roadbed than the ends.

Other objects, as well as the advantages of the construction provided to carry out the invention will appear as the description proceeds.

Reference is to be had to the accompanying drawings forming a part of this specification in which similar reference characters indicate corresponding parts in all the views.

Figure 1 is a side elevation partly in longitudinal vertical section of a railway tie embodying my invention;

Fig. 2 is a plan view;

Fig. 3 is a plan view of the reinforcing structure;

Fig. 4 is a fragmentary side elevation of the reinforcing structure;

Fig. 5 is a cross section on the line 5—5, Fig. 2.

In forming a tie in accordance with my invention, end blocks 10 are produced and a center connecting bar 11.

The reinforcing structure is composed of three longitudinal rods, there being a pair of separated top rods 12 and a bottom rod 13 disposed in a vertical plane between the planes of the top rods 12 and spaced from the latter so that the said reinforcing rods are triangularly disposed as seen best in Figs. 3 and 5 with the center rod at the bottom.

The ends of the three longitudinal rods, 12, 13, are bent and carried into each end block 10. The rods 12 are carried downwardly and outwardly as at 15 and then formed into reinforcing base members 14

in each block 10 at the sides. Transverse rods 16 tie the respective side rods or members 14 together and additional transverse tie rods 17 connect said side members 14 adjacent to the ends of the blocks 10.

The lower longitudinal rod 13 is carried upwardly and outwardly at its ends as at 18 and is then formed into a substantially rectangular top frame 19. At the inner end of each top frame 19, the same extends through the bends 12^a at the juncture of the longitudinal bars 12 and their inclined members 15. At the outer end each top frame 19 is engaged by inclined members 20 integral with and forming the terminals of the longitudinal base rods 14. Thus, the reinforcing elements in each block 10 include a rectangular base frame formed by the members 14, 17, and tied by the members 16, while the top frame 19, which also, is essentially rectangular and smaller than the base frame, is connected with the base frame by the members 15, 20, the whole being of a shape to produce a concrete block in the form of a frustum of a pyramid.

The longitudinal rods, 12, 13, are bound by a spiral wire 21. The lower rod 13 takes up the tensile stresses in the center bar 11 which occur during shipment and installation of the tie, while the two upper rods 12 at the same time assist in taking the compressive stresses in the concrete. The transverse rods 16, 17 assist in taking up the compressive strains due to passing loads, and the said rods 16 also resist the strains of driving the spikes in fixing the rails as hereinafter explained.

The concrete body 22 is molded in a suitable mold which may be of simple construction, owing to the form of my improved tie. In the end blocks 10, vertically disposed pockets or depressions are produced in the concrete to receive wood spike-plugs, each plug being composed of a main member 23 and an auxiliary member 24. The body members 23 of the wood plugs are cut in a vertical plane across the grain of the wood and said body is tapered by beveling a side thereof, and the auxiliary member or section 24, of the plug, is cut with the grain and is slightly tapered. In placing these plugs in the pockets previously molded in the blocks 10, the body member 23 is inserted first, the broad end at the bottom of the pocket, and with the beveled side toward the end of the tie in the case of the outside pockets and toward the center of the tie in

the case of the inside pockets. The smaller plug section 24 is then driven into position and the tie is ready to receive the spikes B for securing the rail A. In the event the 5 spike is withdrawn, the old plug is easily removed by withdrawing the small tapered section 24 and then removing the larger body section 23.

In order to cushion the rails, rectangular 10 flat wood slabs 25 are provided having holes bored for the passage of the spikes B. Thus, in placing a rail a slab 25 is laid on top of the block 10 with the holes in the slab above the plug members 23 so that the spikes B, 15 when driven, will serve to hold the said cushion members 25 in position as well as the rail A.

It is to be observed that the cross rods 16 extend directly beneath the spike plugs 20 so as to resist the strain of driving the spikes into said plugs.

The upward taper of the blocks 10 provides beveled end surfaces 26. The form 25 of the tie is such that the only tamping needed is beneath the blocks 10. The said blocks are formed at the bottom surface with broad recesses 27 occupying a material portion of the total area, the provision of which recesses insures against lateral movement in 30 the roadbed and results in producing a stable track.

The center connecting bar 11, as clearly seen in Fig. 5 is triangular with the inverted apex engaging the roadbed and the 35 apex is elevated above the bottoms of the end blocks. The purpose of the described cross section and of the elevated connecting bar is to prevent the center portion of the tie bearing on the roadbed in a manner 40 to create bending stresses in the tie and also to minimize the possibility of the ties resulting in a center bound roadbed by reason of the center bar bearing more firmly on the bed than the end blocks. The triangular 45 form of the center bar also enables me to produce a bar of maximum strength with a minimum of reinforcing material whereby to keep down the cost of manufacture, looking to the production of the tie at a cost reasonably proportionate to that of a wood tie. I have had in mind also, the commercial 50 requirements of the facility with which the rail is fixed in position without radically departing from the methods involved in the 55 use of wood ties.

Having thus described my invention I claim as new and desire to secure by Letters Patent:

1. A railway tie including concrete end 60 blocks, a concrete bar connecting the blocks, the said bar being triangular in cross section with the base of the triangle uppermost and the inverted apex at the under side, the said

blocks being broader than the said bar, three reinforcing rods ranging longitudinally within the said bar in triangular relation corresponding with the cross section of said bar, and reinforcing elements in the said end blocks, said elements including a substantially rectangular base frame, a substantially rectangular top frame of smaller dimensions than the base frame, cross rods connecting the side members of the base frame at the ends and between the ends, members integral with the longitudinal rods and with the side members of the base frame, and bent around the inner ends of the top frame, and members connecting the base frame and top frame at the outer ends thereof, said members being integral with the side members of the base frame.

2. A railway tie including concrete end blocks and a concrete bar connecting said blocks, the said bar being triangular in cross section with the base of the triangle 8 uppermost, and the said blocks being of greater width than the said bar, each block being in the form of a frustum of a pyramid, reinforcing elements in the said blocks, including top frames and base frames and 9 members connecting said frames at the inner and outer ends, and longitudinal reinforcing rods in the said bar integral with one of said frames, there being three of said rods disposed in triangular relation corresponding with the cross section of the said bar.

3. A railway tie including concrete end blocks, a concrete bar integral with said end blocks, said blocks having pockets therein, 10 wood blocks in said pockets adapted to receive spikes, reinforcing elements in said blocks including base frames and top frames, cross rods connecting the side members of the base frames directly beneath the said 10 pockets, elements connecting the top frame and bottom frame in each block, and longitudinally ranging reinforcing rods in the said concrete bar and connected with the reinforcing elements in the said blocks.

4. A reinforced concrete railway tie including end blocks having vertical pockets therein, plugs in said pockets, each plug being formed of a vertically disposed body member and a vertically disposed auxiliary 11 member, and reinforcing elements in the said blocks, the reinforcing elements including members directly beneath the said pockets.

In testimony whereof I have signed my name to this specification in the presence of 120 two subscribing witnesses.

WILLIAM EDWARD CHESNEY.
